(57) **CLAIM**

The ornamental design for a speaker for home theater, as shown and described.

DESCRIPTION

FIG. 1 is a front, left side, perspective view of a speaker for home theater showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a reference view thereof, showing the speaker in an environment of use equipped on a wall.

The broken lines in FIGS. 3 and 8 are included for the purpose of illustrating portions of the speaker and environment of the speaker and forms no part of the claimed design.
